(57) **CLAIM**

The ornamental design for a razor blade head, as shown and described.

DESCRIPTION

FIG. 1 is a first perspective view of a razor blade head showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1; and,

FIG. 10 is an enlarged view of the selected portion 10 in FIG. 2.

The evenly-spaced broken lines shown in the drawings illustrate portions of the razor blade head and form no part of the claimed design. The dash-dot broken lines illustrate enlarged view indicators and form no part of the claimed design.
